E. RE

MOTOR

Filed Nov. 28, 1923

INVENTOR.

Enrico Re

BY *Watson E. Coleman*
ATTORNEY.

UNITED STATES PATENT OFFICE.

ENRICO RE, OF VINELAND, NEW JERSEY.

MOTOR.

Application filed November 28, 1923. Serial No. 677,493.

To all whom it may concern:

Be it known that I, ENRICO RE, a subject of the King of Italy, residing at Vineland, in the county of Cumberland and State of New Jersey, have invented certain new and useful Improvements in Motors, of which the following is a specification, reference being had to the accompanying drawings.

This invention relates to certain improvements in motors and it is primarily an object of the invention to provide a novel and improved device of this general character especially designed and adapted for use in operating the treadles of the operating mechanism of a player piano.

It is also an object of the invention to provide a novel and improved motor of this general character which is of a spring type and wherein the operating shaft has associated therewith a plurality of spring operated members whereby the device can be constructed in a manner to occupy a minimum of space yet at the same time possess the efficiency desired in a device of this kind.

The invention consists in the details of construction and in the combination and arrangement of the several parts of my improved motor whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view partly in section and partly in elevation illustrating a motor constructed in accordance with an embodiment of my invention;

Figure 2 is a sectional view taken substantially on the line 2—2 of Figure 1;

Figure 3 is a fragmentary sectional view taken longitudinally of Figure 2.

As disclosed in the accompanying drawings, H denotes a housing of suitable dimensions and which is supported at its opposite ends by the pillars or posts P whereby the device may be readily disposed over the treadles T for the operating mechanism of a player piano. The posts or pillars P have associated therewith the casters C whereby the device in its entirety may

be readily moved into or out of working position with respect to the treadles T as may be required.

Rotatably supported within the housing H is a crank shaft 1 which has operatively engaged therewith the pitmen 2 which are adapted to be connected in any preferred manner with the treadles T so that upon rotation of the shaft 1 the treadles T will be operated in a manner to effect the desired functioning of the operating mechanism of the player piano and without the necessity of the treadles being worked by the feet as is now done.

Also supported within the housing H is a second shaft comprising a plurality of sections 3 and mounted on each of said sections is a gear wheel 4 in mesh with the pinion 5 mounted on the shaft 1 so that upon rotation of any one of the gears 4 the shaft 1 will be rotated.

Each of the gears 4 is loosely mounted on the shaft 1 but provided with a pawl or dog 6 associated with the ratchet wheel 7 fixed to the shaft 1. By this means the idle gears 4 offer no obstruction to the rotation of the shaft 1 but upon any one of the gears becoming inactive, the desired rotation of the shaft 1 will be affected.

The gears 4 are also each loosely mounted on a shaft section 3 and is provided with a dog or pawl 8 coacting with the ratchet wheel 9 carried by the shaft section 3. Associated with the gear 4 and the shaft section 3 is a spring 10.

Each of the gears 4 is normally maintained inactive by the pivot dog 11 normally held in locking engagement with the spring by the spring pressed pin 12. A rock lever 14 has one end portion overlying the dog 11 and its opposite end portion disposed over the periphery of an adjacent spring 10 so that as said spring 10 unwinds and is substantially completely run down, said spring will contact with the lever 14 and rock the same in a direction to release the dog 11 whereupon the next succeeding spring and gear 4 will be caused to function. The first lever 14, however, extends exteriorly of the housing H and is adapted to be engaged by a finger or the like to initially start the motor.

Any means, as generally indicated at 15, may be employed for winding the springs 10.

It is also to be understood that the en-

gagement of the pitmen 2 with the treadles T is detachable.

From the foregoing description it is thought to be obvious that a motor constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

In combination with a shaft a plurality

of shaft sections rotatably supported adjacent to the shaft, a gear loosely mounted on each of the shaft sections, a gear loosely mounted on the first named shaft with which said gear of the shaft section meshes, a spring associated with each shaft section and gear thereon for rotating the gear, co-acting means carried by the shaft and each of the gears mounted thereon to cause said gear and shaft to rotate in unison in one direction, means for holding the gears on the shaft sections against rotation, the spring associated with one gear operating when unwound to release the holding means of the succeeding gear.

In testimony whereof I hereunto affix my signature.

ENRICO RE.
